UNITED STATES PATENT OFFICE.

SAMUEL COHEN AND ARTHUR R. FOERSTER, OF NEW YORK, N. Y.

BUTTON DEVICE.

1,353,725.

Specification of Letters Patent. Patented Sept. 21, 1920.

Application filed August 27, 1919. Serial No. 320,114.

To all whom it may concern:

Be it known that we, SAMUEL COHEN and ARTHUR R. FOERSTER, citizens of the United States, and residing at New York, in the 5 county of New York and State of New York, have invented certain new and useful Improvements in Button Devices, of which the following is a specification, such as will enable those skilled in the art to which it 10 appertains to make and use the same.

This invention relates to button devices and particularly to what are known as collar buttons, and the object of the invention is to provide a button of the class specified 15 with a movable, resilient and padded back member which is designed to prevent the discoloring or poisoning of the neck of the wearer as well as to prevent the binding and pinching of the neck of the wearer in 20 the use of the collar button; and with this and other objects in view the invention consists in a device of the class and for the purpose specified, constructed and operating as hereinafter described and claimed.

25 The invention is fully disclosed in the following specification, of which the accompanying drawing forms a part, in which the separate parts of our improvement are designated by suitable reference characters in 30 each of the views, and in which:

Figure 1 is a side view of one of our improved collar buttons showing the same on an enlarged scale;

Fig. 2 a central longitudinal section 35 through the complete button; and,

Fig. 3 a view similar to Fig. 2 but showing only a detail of the construction and showing such detail on an enlarged scale.

In practice, we provide a main button 40 member 5 which is of the usual general form and preferably composed of sheet metal fashioned to form a hollow and approximately spherical head 6, a reduced neck 7 and an enlarged base 8, the bottom 9 of 45 which is provided with a central opening 10.

A supplemental button member 11 is loosely mounted in connection with the main button member 5 and comprises inner and outer disks 12 and 13, the disk 13 being of 50 slightly greater diameter than the disk 12, and these disks are secured together by a central shank portion 14 which passes through and is adapted to operate in the aperture 10.

55 Mounted on the disk 13 of the supplemental button member 11 is an outer fibrous

sheet 15 which is secured in connection with the periphery of the disk 13 by a cup-shaped disk 16 mounted outwardly of the disk 13, and the periphery of the flange 17 of which 60 is bent inwardly and around the periphery of the disk 13 in the form of an annular flange 18 which is approximately hook-shaped in form in cross section.

In securing the fibrous sheet 15 in connection with the disk 13, a suitable padding 19 is first placed between said sheet and disk 16, this padding being preferably composed of sponge rubber but may be composed of any other suitable padding material. After 70 the padding 19 has been placed in position, the edge portions of the sheet 15 are folded around the periphery of the flange 17 of the disk 16 in the manner illustrated in dotted lines in Fig. 3, after which the disk 13 is 75 placed within the cup-shaped disk 16 and the flange 17 bent over and around the periphery of the disk 13 as hereinbefore stated and as clearly shown in Fig. 3.

The above operation securely binds the 80 fibrous or fabric sheet 15 in connection with the disk 13 of the supplemental button member 11 and holds the padding 19 in proper position on the outer face of the disk 13. It will be seen that the disk 12 of the supplemental button member is free to move laterally as well as inwardly and outwardly 85 within the button member 5, or the base 8 thereof, and is also free to rotate therein. We also preferably employ a spiral spring 90 20 which is placed in the base 8 of the button 5 and operates between the reduced neck 7 of the button member 5 and the disk 12 of the supplemental button member 11.

It will be understood that our improved 95 button device, in addition, to its free and unbinding action when in use is also sanitary in use and by using a suitable padding 15 on the outer face of the supplemental button member 11, said button member will 100 tend to absorb any moisture that may be present and will prevent the discoloring of the neck of the wearer, and said supplemental button member will freely move within the button member 5 in the twisting or turning 105 of the neck, and will always adjust itself to a position which will be comfortable to the wearer. It will also be apparent that while we have shown the supplemental button member applied to a specific form and 110 construction of the main button member 5, our invention is not necessarily limited to

this extent, and various changes in and modifications of the construction herein shown and described may be made, within the scope of the appended claims without departing from the spirit of our invention or sacrificing its advantages.

Having fully described our invention, what we claim as new and desire to secure by Letters Patent, is:—

- 10 1. A device of the class described comprising a main button member having a head at one end and an enlarged and hollow base at the other end thereof, and a supplemental button member comprising two heads joined by a shank, one of the heads of the supplemental button member being mounted in the hollow base of the main button member and permanently retained therein in such manner as to permit 15 of lateral, rotatable and inward and outward movements of said supplemental button member in the main button member.
- 20 2. A device of the class described comprising a main button member and a supplemental button member loosely mounted in connection with the base portion of said main button member, and the outer face of said supplemental button member being provided with a fibrous covering.
- 25 3. A device of the class described comprising a main button member and a supplemental button member loosely mounted in connection with the base portion of said main button member, and the outer face of said supplemental button member being provided with a fibrous covering between which and the face of said supplemental button member is a suitable padding.
- 30 4. A device of the class described comprising a main button member, a supplemental button member loosely mounted in connection with the base portion of the main button member, and a spring mounted within the main button member and adapted to 35 normally move the supplemental button member outwardly.
- 40 5. A device of the class described comprising a main button member, a supplemental button member loosely mounted in connection with the base portion of the main button member, a spring mounted within the main button member and adapted to normally move the supplemental button member outwardly, and means on said supplemental button member for holding it 45 against detachment from said main button member.
- 50 6. A device of the class described comprising a main button member, a supplemental button member loosely mounted in connection with the base portion of the main button member, a spring mounted within the main button member and adapted to normally move the supplemental button member outwardly, and means on said supplemental button member for holding it 55 against detachment from said main button member.
- 60 7. A device of the class described comprising a main button member, a supplemental button member loosely mounted in connection with the base portion of the main button member, a spring mounted within the main button member and adapted to normally move the supplemental button member outwardly.

member outwardly, and means on said supplemental button member for holding it against detachment from said main button member and the protruding portion of said supplemental button member being provided with a fabric covering.

7. A device of the class described comprising a main button member, a supplemental button member loosely mounted in connection with the base portion of the main button member, a spring mounted within the main button member and adapted to normally move the supplemental button member outwardly, means on said supplemental button member for holding it against detachment from said main button member and the protruding portion of said supplemental button member being provided with a fabric covering, and means for securing said covering in connection with said supplemental button member.

8. A device of the class described comprising a main button member, a supplemental button member loosely mounted in connection with the base portion of the main button member, a spring mounted within the main button member and adapted to normally move the supplemental button member outwardly, means on said supplemental button member for holding it against detachment from said main button member and the protruding portion of said supplemental button member being provided with a fabric covering, and means for securing said covering in connection with said supplemental button member, and a suitable padding mounted within said fabric covering.

9. A collar button of the class described comprising a main button member, a supplemental button member comprising two disks joined by a reduced neck portion, one of said disks being permanently retained within the base portion of the main button member and freely movable therein, and the other of said disks being provided with a fibrous covering.

10. A device of the class described comprising a main button member consisting of a head, a shank and a hollow base, and a supplemental button member loosely and permanently mounted in the hollow base of the main button member and provided outwardly of said base with a disk-shaped head.

In testimony that we claim the foregoing as our invention we have signed our names in presence of the subscribing witnesses this 26th day of August 1919.

SAMUEL COHEN.
ARTHUR R. FOERSTER.
